(57) CLAIM

The ornamental design for a container for produce, as shown and described.

DESCRIPTION

FIG. 1 is a front, top perspective view of a container for produce showing my new design;

FIG. 2 is a front, top perspective view thereof showing exemplary produce within; and,

FIG. 3 is a front view thereof.

The broken line portion of the figure drawings is included to show unclaimed subject matter only and forms no part of the claimed design.

1 Claim, 3 Drawing Sheets

FIG. 3
